UNITED STATES PATENT OFFICE

142,756

DESIGN FOR A HAND MIRROR

Samuel J. Winslow, Providence, R. I.

Application February 19, 1945, Serial No. 118,021

Term of patent 7 years

(Cl. D86—10)

To all whom it may concern:

Be it known that I, Samuel J. Winslow, a citizen of the United States, residing at Providence, in the county of Providence and State of Rhode Island, have invented a new, original, and ornamental Design for Hand Mirrors, of which the following is a specification, reference being had to the accompanying drawing, forming part thereof.

In the drawing,

Fig. 1 is a front elevational view of a hand mirror showing my new design;

Fig. 2 is a side elevational view thereof; and Fig. 3 is a sectional view thereof taken on line 3—3 of Fig. 1.

The back of the mirror is substantially like the front shown.

I claim:

The ornamental design for a hand mirror, as shown and described.

SAMUEL J. WINSLOW.
